(57) **CLAIM**

We claim the ornamental design for a dispensing fitment, as shown and described.

DESCRIPTION

FIG. 1 is a front perspective view of a dispensing fitment according to a first embodiment of the present invention. FIG. 2 is a rear perspective view of the dispensing fitment of FIG. 1.

FIG. 3 is a left-side view of the dispensing fitment of FIG. 1.

FIG. 4 is a right-side view of the dispensing fitment of FIG. 1.

FIG. 5 is a front view of the dispensing fitment of FIG. 1.

FIG. 6 is a rear view of the dispensing fitment of FIG. 1.

FIG. 7 is a top view of the dispensing fitment of FIG. 1; and,

FIG. 8 is a bottom view of the dispensing fitment of FIG. 1.

The portions of the dispensing fitment shown in broken lines are included for the purpose of illustrating environment and form no part of the claimed design. The portions of the dispensing fitment shown in broken lines having unequal length segments illustrate the boundary of the claimed design and form no part of the claimed design.

1 Claim, 6 Drawing Sheets
